UNITED STATES PATENT OFFICE.

ERNEST E. SIEVERT, OF MANISTEE, MICHIGAN.

WRENCH.

1,368,580.

Specification of Letters Patent.

Patented Feb. 15, 1921.

Application filed August 12, 1920. Serial No. 402,966.

To all whom it may concern:

Be it known that I, ERNEST E. SIEVERT, a citizen of the United States, residing at Manistee, in the county of Manistee and 5 State of Michigan, have invented certain new and useful Improvements in Wrenches; and I do declare the following to be a full, clear, and exact description of the invention, such as will enable others skilled in the art to 10 which it appertains to make and use the same.

This invention relates to improvements in wrenches.

The principal object of the invention is 15 to generally improve upon devices of this class by producing one including a movable jaw which is retained in various adjusted positions by means which is such that it permits it to be very easily and quickly 20 moved toward and from the stationary jaw, this means being novel and very convenient to manipulate and retaining the jaw in the position to which it has been adjusted without permitting it to slip.

25 Other objects and advantages of the invention will be apparent during the course of the following description.

In the accompanying drawings forming a 30 part of this specification and in which like numerals are employed to designate like parts throughout the same:

Figure 1 is a side elevation of a wrench constructed in accordance with my invention.

35 Fig. 2 is a similar view with the movable jaw in section to more clearly disclose the improved locking means therefor.

Fig. 3 is an end elevation thereof.

Fig. 4 is a transverse section taken on the 40 line 4—4 of Fig. 2, looking in the direction of the arrows.

Fig. 5 is a slightly modified form of the invention, with parts broken away to disclose the construction clearly.

45 Referring to the drawings, wherein the preferred embodiment of my invention is illustrated, the numeral 1 designates a shank, at the outer end of which is a laterally extending rigid jaw 2 and on the inner 50 side of which are ratchet-teeth 3. Slidably mounted on this shank is a movable jaw 4 which is provided in one side with a recess 5, in the outer wall of which a seat 6 is formed, the latter being at a point remote 55 from the ratchet teeth 3. This seat consti-

tutes a bearing for the rounded end of the dog 7 which is fulcrumed therein, the latter being provided at its free end with a plurality of teeth for engagement with said ratchet teeth. In order to retain the dog in 60 effective engagement with the ratchet teeth, I employ a spring 8, preferably of U-shape, the same having one of its ends anchored in the inner wall of the recess 5 and its other end secured to one side of the dog. I employ novel means for disengaging the dog. 65 This means preferably consists of a yoke 9 which is disposed in the slot 10 formed in the other side of the movable jaw, the arms of this yoke straddling the shank 1 and extending into close proximity of the inner 70 ends of the slot 10, and the extremities of these arms being reduced as shown at 11 and laterally off-set. These laterally off-set extremities 11 are connected by a bar 12, and this bar in conjunction with them constitutes a cam which bears on the inclined dog 75 and disengages it when the yoke 9 is moved in a direction transverse of the shank, as is 80 obvious.

In Fig. 5 I have disclosed, as before stated, a slightly modified form of my invention. By referring to this figure it will be seen that a different type of wrench is disclosed. This wrench includes a shank 13 85 provided at its outer end with a recessed and slotted head 14 which in turn carries a stationary jaw 15. At this point, I wish to mention that for the sake of convenience and clearness, the parts of the device disclosed in this form of the invention which are like the parts disclosed in the already 90 described form, will be designated by the same numerals. To this end, the numeral 16 designates the rounded seat in said recessed head in which the rounded end of the dog 7 is fulcrumed, the latter being retained in position by the same type of spring 8 which coacts therewith in a like 95 manner. The dog in this form of the invention is provided in one side with a notch 16, the purpose of which will be hereinafter described. The movable jaw 17 carries a laterally extending shank 18 which is slid- 100 able in the slot in the head 14, this shank 105 being provided along the edge adjacent the recess with ratchet teeth with which the teeth of the dog coact. A plunger 19 is employed for the purpose of disengaging the dog, the stem of the same extending through 110

a hole formed in the head 14 and the inner end thereof being seated in said notch 16 to insure effective coöperation of the parts.

- To adjust the jaw 4, the connecting portion of the yoke 9 is pressed in, that is moved in a direction transverse of the shank 1, by the thumb or finger. Such movement of this yoke will cause the cam carried thereby to ride along the inclined dog in such a manner as to disengage it. As soon as pressure on the yoke is released, the spring 8 will automatically return the dog to effective position so as to retain the jaw in position to which it has been adjusted.
- 15 To operate the form of the invention disclosed in Fig. 5, it is obvious that it is only necessary to press the plunger 19 inwardly which will disengage the dog and permit quick adjustment of the movable jaw.
- 20 From the foregoing description taken in connection with the accompanying drawings, the operation of my device will be readily understood, therefore, further description is deemed unnecessary.

25 I claim:

1. A wrench of the type described comprising a stationary jaw and a movable jaw, one of said jaws including a shank provided along one side with ratchet-teeth, and the other jaw being provided with a recess in which a rounded seat is formed, a pawl arranged in said recess and extending at an acute angle with respect to said shank, one of its ends being rounded and loosely fulcrumed in said seat, its other end being beveled and provided with a plurality of teeth engageable with said ratchet-teeth, means carried by one of the jaws and engageable with one edge of the pawl for disengaging the latter, and a spring arranged in the aforesaid recess and bearing against the op-

posite edge of the pawl for retaining it in position in said seat and for holding it in effective engagement with said ratchet-teeth.

2. A wrench comprising a shank provided along one side with ratchet-teeth and at one end with a rigid jaw, a movable jaw slidable on said shank, being provided in one end with a vertical recess, constituting an open chamber, being also provided in its opposite sides with opposed horizontal slots communicating with said chamber, the said chamber having a rounded seat formed in an upper corner remote from said shank, a dog arranged in said chamber and extending at an acute angle with respect to said shank, one end thereof being rounded and detachably fulcrumed in said seat, the other end being beveled and provided with a plurality of teeth engageable with the aforesaid ratchet-teeth, a substantially rectangular ring-like member surrounding and slidable on the shank, being disposed in said opposed horizontal slots and having its inner end extending into said chamber, said inner end being laterally offset and reduced in width and forming a cam bearing on the upper edge of the dog for disengaging the latter when said member is moved toward 70 or crosswise of said shank, and a V-shaped spring in said chamber, having one of its ends anchored in the lower wall of said chamber and its opposite end secured to the lower edge of said dog to retain the latter 75 in position in its seat and to hold it in effective engagement with the aforesaid ratchet-teeth.

In testimony whereof I have hereunto set my hand.

ERNEST E. SIEVERT.
